UNITED STATES PATENT OFFICE.

VICTOR C. RUMBERG, OF OGEMA, WISCONSIN.

LOCK.

Application filed July 5, 1924. Serial No. 724,500.

To all whom it may concern:

Be it known that I, VICTOR C. RUMBERG, a citizen of the United States, residing at Ogema, in the county of Price and State of Wisconsin, have invented a new and useful Lock, of which the following is a specification.

This invention aims to provide an exceedingly simple means whereby the bolt of a lock can be operated only by a person who is acquainted with the construction of the lock, the lock being devoid of all of those complications which arise out of the use of permutation or combination mechanisms.

It is within the province of the disclosure to improve generally and to enhance the utility of devices of that type to which the invention appertains.

Although a preferred form of the invention has been shown, it will be understood that a locksmith, working within the scope of what is claimed, may make changes and alterations without departing from the spirit of the invention.

In the drawings:—Figure 1 shows in elevation, a portion of a barrier whereunto the device forming the subject matter of this application has been applied; Figure 2 is a section taken about on the line 2—2 of Figure 1; Figure 3 is an elevation showing the lock case and attendant parts, the lid having been removed; Figure 4 is a perspective view showing the bolt; Figure 5 is a perspective view disclosing the yoke; Figure 6 is a perspective view wherein one end of the spindle appears.

The device forming the subject matter of this application comprises a casing which may be mounted on the outer surface of a door or other barrier, or be morticed into the edge of the barrier. The construction last mentioned has been selected for illustration, but the manner of mounting the casing on the barrier is left to the mechanic.

The numeral 1 marks a door or other barrier in which is mounted a casing 2, comprising a box-like body 3 and a lid 4, the lid being attached to the body of the casing by securing elements 5 engaged with lugs 6 within the body 3 of the casing. One end of the body 3 carries a face plate 7 adapted to be secured in the usual way to the edge of the barrier 1.

A bolt 8, having a beveled end 9, slides between the lugs 6 and projects through

an opening 10 in the face plate 7, the bolt being provided with diverging arms 11 having angular fingers 12 adapted to cooperate with the ends of a yoke 14 including a socket 15 provided with an opening 16. The body 3 of the casing carries an abutment 17 which is secured at 18 to the body, the abutment carrying a compression spring 19 engaged in a longitudinal seat 20 in the locking bolt 8 and serving to advance the locking bolt.

The numeral 21 marks a spindle extended through the barrier 1 and through the casing 2, the spindle being provided with a flattened side 22, the spindle extending 70 through the opening 16 of the yoke 14, and the opening being so shaped as to cooperate with the flat side 22 of the spindle 21 the construction being such that when the spindle is rotated, the yoke 14 will be rocked, to 75 retract the bolt 8 in the usual way. A knob 23 may be secured at 24 to one end of the spindle 21, the knob 23 being located on the inside of the barrier or door 1. The opposite end of the spindle 21 is provided with 80 an enlarged disk-like head 25. A knob 26 is located on the outside of the door 1 and is journaled for free rotation on the spindle, the knob 26 having a bore 27 for the reception of the spindle, and being provided in 85 its outer end with a recess 28 wherein the head 25 of the spindle is received, the outer surface of the head 25 being flush with the outer end surface of the knob 26. The inner ends of the knobs 23 and 26 are journaled 90 within collars 29 on finishing plates 30 secured at 31 to opposite surfaces of the barrier 1.

When a person who is unacquainted with the construction of the lock attempts to operate the lock from the outside of the barrier 1, the knob 26 merely rotates on the spindle and the yoke 14 does not operate to retract the bolt 8. A person who is acquainted with the operation of the device 95 will grip the knob 26 between the second finger and forefinger, the thumb being pressed against the head 25 of the spindle 21, the knob 26 being bound against the head 25, and rotation being imparted to the spindle 21, the bolt 8 being retracted through the instrumentality of the yoke 14. The head 25 of the spindle 21 sets in flush with the outer end surface of the knob 26 105 and, to the eye of a casual observer, will 110

suggest merely an ornamentation on the knob, and not some part by which the lock may be manipulated.

What is claimed is:—

- 5 1. A device of the class described comprising a rotatable spindle, a locking means under the control of the spindle, and a knob freely rotatable on the spindle, the spindle comprising an exposed part so located with respect to the knob that said part may be engaged by the hand of an operator, when 10 the hand of the operator is on the knob.
- 10 2. A device of the class described comprising a rotatable spindle having a head, a locking means under the control of the spin- 15

dle, and a knob freely rotatable on the spindle, the head being located at the outer end of the spindle and being so located with respect to the knob that said part may be engaged by the hand of an operator, when 20 the hand of the operator is on the knob.

3. A device of the class described, constructed as set forth in claim 2, and further characterized by the fact that the outer surface of the head is approximately flush with the outer end surface of the knob, the knob having a recess wherein the head is received.

In testimony that I claim the foregoing as my own, I have hereto affixed my signature.

VICTOR C. RUMBERG.
